YARN TENSIONING DEVICE FOR TEXTILE MACHINES

Fritz Lambach, Tenafly, and Walter Siegel, Union City, N. J., assignors to Robert Reiner, Inc., Weehawken, N. J.

Application May 27, 1944, Serial No. 537,678

8 Claims. (Cl. 242—154)

Our invention relates to textile machines, and more particularly to a yarn tensioning device for textile machines.

An object of our invention is to provide a yarn tensioning device, which may be readily adjusted for a proper tensioning of yarns of different sizes and/or qualities.

Another object of our invention is to provide an adjustable yarn tensioning device, which may be manufactured at low costs.

A further object of our invention is to provide an adjustable yarn tensioning device, wherein the parts subject to great wear and tear may be readily replaced by new parts, so that it is unnecessary to replace the entire yarn tensioning device if only a part thereof is worn out.

Still another object of our invention is to improve upon yarn tensioning devices for textile machines as now ordinarily made.

In order to carry out our invention in practice we provide a yarn tensioning device for textile machines, comprising a support, guiding means on said support, a plurality of pins arranged on said support for engagement with a yarn trained around a selected number of pins, at least one of said pins being in slidable engagement with said guiding means for an adjustment of the angle of contact between the yarn and the pins, means for holding the adjustable pin in an adjusted position, supporting surfaces surrounding said pins, and a disc detachably mounted on each of said pins, each of said discs resting on the supporting surface surrounding the pin for braking engagement with the yarn trained around the pins and placed between the discs and the supporting surface.

The above mentioned objects and advantages as well as other objects and advantages will be more fully disclosed in the following specification reference being had to the accompanying drawing forming part of this specification, wherein:

Fig. 1 is a top plan view of a yarn tensioning device according to the invention, partly in section, said yarn tensioning device being equipped with detachable braking discs on one of its pins engaging the yarn.

Fig. 2 is a front elevational view of the yarn tensioning device shown in Fig. 1, partly in section.

Fig. 3 is a side elevational view of the yarn tensioning device shown in Fig. 1, and

Fig. 4 is a top plan view of the yarn tensioning device shown in Fig. 1, wherein, however, detachable braking discs are arranged on both pins, some parts being broken away.

Referring now to the drawing, 10 indicates the

support or base of the yarn tensioning device. Said support 10 has a recess 12 for engagement with a member of a textile machine, for example for engagement with a post 14 of a creel carrying bobbins of yarn to be wound on a beam or the like. The support may be attached to the member 14 by means of a screw 16 threaded into a threaded bore of the support.

10 A yarn protecting funnel 18 having a center hole 19 is mounted on a shoulder 20 of a lug 22 extending upwardly from the support 10. Said funnel is held in its position by the flange of an eyelet 24 inserted into an aperture of said lug 22 and held therein by a split ring 26 being in engagement with a circular groove of the eyelet and resting against the surface of the lug.

15 A second eyelet 28 is inserted into the opening of a second lug 30 extending upwardly from the support 10. Said eyelet 28 is held in its position by a split ring 32 engaged with a circular groove of the eyelet.

20 As will be readily understood from above, the use of split rings for securing the eyelets 24 and 28 to the lugs of the support permits an easy replacement of the eyelets by new ones, if they should be worn out after a period of time, so that it becomes unnecessary to replace the entire yarn tensioning device on the textile machine by a new one, if only an eyelet of the tensioning device is worn out.

25 The support 10 is provided with two slots generally indicated by 34 and 36. The slot 34 is comprised of two portions 38 and 40 merging in each other and being arranged at a right angle to each other. A first pin 42 is slidably and adjustably mounted in the slot 34 forming a guide for said first pin 42, and a second pin 44 is slidably and adjustably mounted in the slot 36 forming a guide for said second pin 44. Preferably, the mounting of the first pin 42 in the slot or guide 34 is exactly the same as the mounting of the second pin 44 in the slot or guide 36, so that it is sufficient to describe hereinafter, only the mounting of the second pin as best shown in Fig. 2.

30 According to said Fig. 2, the hollow pin 44 rests on a washer 46 placed on the surface of the support 10. A setting screw 48 passing through the hollow pin 44, the bore of the washer 46 and the slot 36 has its end threaded into a square nut 50 being in engagement with a lip 52 projecting downwardly from the support 10. The lip 52 serves to prevent the square nut 50 from rotating when the setting screw 48 is rotated by a screw driver. If it is desired to set the hollow pin 44 in a predetermined position, the screw 48 is loosened, whereupon the screw 48 together with the hollow

pin 44 and washer 46 may be shifted into said predetermined position by sliding same along the guiding slot 36. Thereupon the hollow pin 44 may be firmly held in the adjusted position by tightening the screw 48 by means of a screw driver.

As mentioned above, the hollow pin 42 resting on a washer 53 may be adjusted in a predetermined position along the portions 38 and 40 of the slot 34 in a similar manner as the hollow pin 44 may be adjusted in a predetermined position along the slot 36. The hollow pin 42 may be held in its adjusted position by means of a setting screw 54.

Preferably, scales are arranged near to the slots 34 and 36 as shown in Fig. 1, so that the operator may readily adjust the pins 42 and 44 in predetermined positions according to a table indicating certain positions by numbers for certain yarns of a certain size and quality.

Fig. 1 illustrates an example of the application of the yarn tensioning device in practice. According to the showing of said Fig. 1, the yarn 56 travelling in the direction of the arrows from a supply (for example a bobbin in the creel, not shown) to an active element or elements of a textile machine (for example the beam of a warping machine, not shown) enters the tensioning device through the eyelet 24, is trained around both pins 42 and 44, and leaves the tensioning device through the eyelet 28. The friction caused by the contact of the travelling yarn 56 with the surfaces of the pins 42 and 44 has a braking effect on the yarn resulting in a tension in the yarn drawn by the element or elements of the textile machines from the supply.

Said braking effect of the tensioning device on the yarn may be varied in many ways depending on the requirements of the yarn of a certain size and quality to be passed through the tensioning device.

For example both pins 42, 44 or either one of said two pins may be equipped with additional braking means. According to Figs. 1-3 such additional braking means are arranged on the pin 44 and will be described hereinafter. A ring 58 of felt or the like surrounding the pin 44 is placed on the surface of the support 10. Said ring 58 carries a disc 60 loosely and detachably mounted on the pin 44. Another disc 62 detachably and rotatably mounted on the pin 44 rests on the first mentioned disc 60. Preferably, said disc 62 is loaded by a plurality of weights 64 detachably and rotatably mounted on the pin 44. If said additional braking means is used, the yarn trained around the pin 44 is placed between the discs 60 and 62. The ring 58 of felt prevents the disc 60 from rotation by the travelling yarn or reduces the rotation of the disc 60 to a minimum, while the disc 62 may freely rotate. As will be readily understood the discs 60 and 62 have an additional braking effect on the yarn. If a still greater braking effect is desired one disc or both discs may be mounted on the pin 44 in such a way, that they are positively prevented from rotation, for example by the arrangement of a key.

Fig. 4 illustrates the arrangement of such additional braking means on both pins 42 and 44 of the yarn tensioning device. Again, a pair of braking discs 60, 62 and a plurality of weights 64 are detachably and rotatably mounted on the pin 44. Furthermore, another pair of braking discs 160, 162 and another set of weights 164 are detachably and rotatably mounted on the pin 42. The construction and arrangement of the discs 160, 162 and weights 164 fully corresponds to that of the

discs 60, 62 and weights 64, so that a detailed description is unnecessary. According to Fig. 4, the yarn 56 trained around the pins 44 and 42 is placed between the discs 60, 62 and between the discs 160, 162.

As will be apparent from above, it is optional to the operator to arrange the detachable additional braking means of the type described above or of a similar type on either one of the two pins 42 and 44 or on both pins, if an increased braking effect is desired. Thus, the additional braking means represent one means for a variation in the braking effect of the yarn tensioning device so as to adjust same for the yarn to be tensioned.

Another means for a variation in the braking effect of the yarn tensioning device may be found in the above described adjustability of the pins 42 and 44 with or without the detachable additional braking means on one pin or both pins. For example, the first pin 42 may be brought from the position shown in full lines in Fig. 1 into the position 42' shown in dash and dot lines, and the second pin 44 may be brought from the position shown in full lines into the position 44' shown in dash and dot lines. This adjustment of the pins causes a change in the angles of contact between the yarn and the pins, which in turn results in a change of the friction, causing a different braking effect. Of course, if desired, only one of the two pins may be adjusted in a different position for a change in the angle of contact between the yarn and the pins, or the pin or pins may be adjusted in intermediate positions, or the pin 42 may be displaced in the portion 40 of the slot 34 instead of the portion 38 thereof.

Moreover, if desired, only one of the two pins 42, 44 may be used for engagement with the yarn, whereby a further change in the braking effect is obtained. For example, only the pin 42 may be used with or without the above described additional braking means; in such a case the yarn 56 entering the tensioning device through the eyelet 24 contacts the pin 42 first on its right hand side (as viewed in Fig. 1) and travels around the pin towards the eyelet 28. Furthermore, if only the pin 42 is used for tensioning the yarn, the pin 42 may be adjusted in different positions along the portion 38 or 40 of the slot 34 for a change in the angle of contact between the yarn and the pin.

As will be apparent from above, the tensioning device may be used in many different combinations and adjustments of its elements. The additional braking elements, i. e., the pair of discs 60, 62, may be omitted, or may be arranged only on the pin 42, or may be arranged only on the pin 44, or may be arranged on both pins 42 and 44. Furthermore, the pins 42, 44 with or without additional braking means may be adjusted in many different positions relative to each other.

We have described a preferred embodiment of our invention, but it is clear that numerous changes and omissions may be made without departing from the spirit of our invention. For example, the guiding slots 34, 36 may be of different shape, or any other type of guides may be used for the slidable and adjustable arrangement of the pins or posts 42, 44. Furthermore, the discs 60 carrying the discs 62 may be replaced by different surfaces surrounding the pins; for example, the construction of the support 10 could be modified in such a way, that the discs 62 could rest on the surface of the support. Moreover, the tensioning device may be equipped with one, two, three, or more pins of which one, two, three, or more are adjustable. Furthermore it is

mentioned, that the use of the tensioning device is not limited to the use in creels, that however the tensioning device may be used in combination with any textile machine wherein yarn should be tensioned.

What we claim is:

1. A yarn tensioning device for textile machines, comprising a support, guiding means on said support, a plurality of pins arranged on said support for engagement with a yarn trained around a selected number of pins, at least one of said pins being in slidable engagement with said guiding means for an adjustment of the angle of contact between the yarn and the pins, means for holding the adjustable pin in an adjusted position, supporting surfaces surrounding said pins, and a disc detachably mounted on each of said pins, each of said discs resting on the supporting surface surrounding the pin for braking engagement with the yarn trained around the pins and placed between the discs and the supporting surface.

2. A yarn tensioning device for textile machines, comprising a support, a plurality of pins arranged on said support for engagement with a yarn trained around a selected number of pins, said support having slots, at least two of said pins being slidably mounted in said slots for an adjustment of the angle of contact between the yarn and the pins, means for holding the adjustable pins in an adjusted position, supporting surfaces surrounding said pins, and a disc detachably mounted on each of said pins, each of said discs resting on the supporting surface surrounding the pins for braking engagement with the yarn trained around the pin and placed between the disc and the supporting surface.

3. In a yarn tensioning device as claimed in claim 2, said discs being rotatably mounted on said pins.

4. A yarn tensioning device for textile machines, comprising a support, guiding means on said support, a plurality of pins arranged on said support for engagement with a yarn trained around a selected number of pins, at least one

5 10 15 20 25 30 35 40 45

of said pins being in slidable engagement with said guiding means for an adjustment of the angle of contact between the yarn and the pins, means for holding the adjustable pin in an adjusted position, and a pair of discs detachably mounted on each of said pins for braking engagement with the yarn trained around the pins and placed between the discs of said pairs of discs.

5. In a yarn tensioning device as claimed in claim 1, said discs being rotatably mounted on said pins.

6. A yarn tensioning device for textile machines, comprising a support, a first guide on said support, a second guide on said support, a first pin and a second pin arranged on said support for engagement with a yarn trained around at least one of said pins, said first pin being slidably and adjustably engaged with said first guide, said second pin being slidably and adjustably engaged with said second guide, and means for holding the pins in adjusted positions, said support having an opening for the passage of the yarn travelling toward said first pin, and said first guide being shaped for adjusting said first pin in a direction substantially parallel to the longitudinal axis of said opening and in a direction at an angle to said longitudinal axis of said opening.

7. In a yarn tensioning device as claimed in claim 6, said first guide comprising a slot having two portions merging in each other and being arranged at an angle to each other, the longitudinal axis of one of said two portions of the slot being substantially parallel to the longitudinal axis of said opening, and said first pin being slidably and adjustably mounted in said slot.

8. In a yarn tensioning device as claimed in claim 6, a pair of discs detachably mounted on each of said pins for braking engagement with the yarn trained around the pins and placed between the discs of said pairs of discs.
